UNITED STATES PATENT OFFICE.

DORA G. MARCUS, OF NEW YORK, N. Y.

DESIGN FOR A PILLOW-SLIP AND PILLOW.

50,583.

Specification for Design.

Patented Apr. 10, 1917.

Application filed January 2, 1917. Serial No. 140,317. Term of patent 3½ years.

To all whom it may concern:

Be it known that I, DORA G. MARCUS, a citizen of the United States, residing at New York city, in the county of New York and State of New York, have invented a new, original, and ornamental Design for a Pillow-Slip and Pillow, of which the following is a specification, reference being had to the accompanying drawing, forming part thereof.

The figure is a perspective view of a pillow slip and pillow showing my new design.

Referring to the drawing, especially to the features which are most prominent, the design consists of the face 10 painted on the pillow which is visible through a corresponding aperture formed in the pillow slip

11. About the face is embroidered on the pillow slip 11, headdress 12, and the garment 13. Bows 14 may be made of ribbon attached to the pillow slip. The pillow case visible through the embroidery and the aperture is of a color different from the pillow slip forming an artistic contrast. I have referred, as above stated, to the features of the design which are most prominent; for details reference may be had to the drawing.

I claim:

The ornamental design for a pillow slip and pillow, as shown and described.

DORA G. MARCUS.

Witnesses:

NATHAN COHEN,
MINNIE S. MILLER.
